UNITED STATES PATENT OFFICE.

ROBERT WOODS, OF GRAND FORKS, NORTH DAKOTA, ASSIGNOR OF ONE-FOURTH TO
PATRICK J. MULLOY, OF GRAND FORKS, NORTH DAKOTA.

DOOR.

974,327

Specification of Letters Patent.

Patented Nov. 1, 1910.

Application filed May 12, 1909. Serial No. 495,380.

To all whom it may concern:

Be it known that I, ROBERT Woods, of Grand Forks, in the county of Grand Forks and State of North Dakota, have invented 5 certain new and useful Improvements in Doors; and I do hereby declare the following to be a full, clear, and exact description of the invention, such as will enable others skilled in the art to which it appertains to 10 make and use the same.

This invention relates to improvements in doors and more particularly to such as are adaptable for use on grain cars, warehouses, freight depots and similar structures, the 15 object of the invention being to provide a vertically movable collapsible door which can be easily raised and disposed in compact form above the door opening.

A further object is to provide simple and 20 efficient means whereby a vertically movable, collapsible door can be securely locked and its sections held tightly when the door is in its closed position.

With these objects in view the invention 25 consists in certain novel features of construction and combinations of parts as hereinafter set forth and pointed out in the claims.

In the accompanying drawings, Figure 1 30 is an inner face view of a door structure embodying my improvements. Fig. 2 is an outer face view of the same. Fig. 3 is a vertical section and Fig. 4 is a sectional view showing the locking means.

1 represents a door frame, to the inner sides of the posts of which, grooved guide-ways 2 are secured and the upper ends of these guide-ways are curved inwardly as 35 most clearly shown in Fig. 3. A sectional or collapsible door 3 is disposed between the guide-ways and the ends of the sections of said door are movable in said guide-ways. The sections of the door are preferably 40 made of metal and the lower section 4 is provided at its lower edge with an inwardly projecting flange 5 and at its upper edge with an outwardly projecting flange 6. Each of the superimposed sections of the door is provided at the upper edge with an 45 outwardly projecting flange 7. Headed pins 8 project outwardly from the upper edges of the several door sections and the pins of one door section receive slotted links or loops 9 which depend from the upper edge 50 of the superimposed section, such construc-

tion serving at all times to maintain the door sections in proper relation to each other and preventing their separation from each other.

Vertical locking bars 10 are located within the grooved guide-ways 2 and provided at their respective ends with journals or pintles 11 mounted in suitable bearings provided for the same. At the lower end, each locking bar is provided with a shoulder 12 which, when the locking bar is turned will 60 become disposed over the inwardly projecting flange 5 at the lower edge of the lower door section 4 and serves to hold the latter tightly against the sill of the door-way. The upper 65 end of each locking bar 10 is provided with an arm 13, which, when the locking bar is turned, will be made to project across the grooved-guide-way 2 over the upper door section and enter a notch 14 in one wall of 70 said guide-way. The arm 13 of each locking-bar projects outwardly beyond the notched wall of the guide-way and enters 75 between perforated lugs 15 on said guide-way, in which position it will be securely 80 locked by a pin 17 passing through said perforated lugs. The arms 13 of the locking bars will thus hold the door against 85 upward movement. Each locking bar 10 is provided with a series of notches for the accommodation of the several door sections 90 so as to permit said door sections to be held closely together and said notches form shoulders 18 which engage the lower edges of the respective door sections and prevent 95 any movement of the latter independently of each other when the door is in its closed position.

To limit the downward movement of the door sections when the door is being closed, 95 the upper section is connected by means of a chain 19 with the top of the door frame.

Near the top of the door frame and in proximity to the curved portions of the grooved guide-ways 2, bearings 20 are located for the accommodation of a horizontal shaft 21. On this shaft (preferably in proximity to the respective ends thereof) chains 22 are adapted to wind and the lower ends of these chains are connected with the door section 4 in proximity to the lower edge of 100 the latter. When the locking-bars shall have been turned so as to release the door, 105 the latter can be raised by turning the shaft 21 to wind the chains 22 thereon. During 110

such raising operation the door section will be collapsed and in such collapsed condition will be raised to the curved portions of the grooved guide-ways 2 and thus be disposed over the top of the door opening. The shaft 21 may be rotated by suitable ratchet mechanism or in any other preferred manner, but in the drawings I have shown said shaft provided with a drum 23 for the reception of an operating chain or cord 24 by means of which to turn it and this drum is shown as being provided with a ratchet wheel 25 to be engaged by a dog 26. This dog is attached to the door frame in such manner that it can be disengaged from the ratchet wheel to permit the latter to turn freely when the door is allowed to descend in closing. The speed of descent can be readily controlled by the operator with the use of the chain or cord 24 on the drum 23.

Various slight changes might be made in the details of construction of my invention without departing from the spirit thereof or limiting its scope and hence I do not wish to restrict myself to the precise details herein set forth, but,—

Having fully described my invention what I claim as new and desire to secure by Letters-Patent, is,—

30 1. A door structure comprising a vertical movable collapsible door, and an upright, oscillatory locking bar for said door mounted in fixed bearings.

35 2. A door structure comprising a series of relatively movable members, and oscillatory locking bars, each mounted in fixed bearings adjacent to respective side edges of the door.

40 3. A door structure comprising a plurality of relatively movable members, and an oscillatory, upright locking bar mounted in fixed bearings and adapted to engage the upper and lower members of the door.

45 4. A door structure comprising a series of vertically movable sections movable relatively to each other and a locking bar having a part to project over the upper section and a part to engage the lower section.

5. A door structure comprising grooved

guide-ways, a door comprising relatively movable sections movable in said guide-ways, the lower section having a projection, and a locking bar having a part to project across the guide-way over the upper section of the door, said locking bar also having a shoulder at its lower end to engage the projection on the lower section of the door.

6. A door structure comprising two grooved guide-ways, a door comprising relatively movable sections movable in said guide-ways, a locking bar mounted in each guide-way and adapted to be turned, each of said locking bars provided at its upper end with an arm to project across the grooved guide-way in which said locking bar is mounted, locking means to engage said arms to lock the locking bars and each of said locking bars provided at its lower end to engage the lower door section and hold the same tightly against the sill of the door-way.

7. A door structure comprising slotted 70 guide-ways having curved upper ends, a door comprising relatively movable sections movable in said guide-ways, means connected with the lower door section for raising the door and collapsing the same in the 75 curved portions of the guide-ways, and means connected with the upper door section for supporting the door in its closed position with the sections thereof distended.

8. A door structure comprising guide-ways and a collapsible door movable in said guide-ways, said door comprising a series of sections movable relatively to each other and each having a flange at one edge, headed pins projecting from relatively movable sections, and links or loops secured to said sections, the links or loops of one section engaging the headed pins of the next lower section.

In testimony whereof, I have signed this 90 specification in the presence of two subscribing witnesses.

ROBERT WOODS.
